COMBINED TOY AND EXERCISER

Filed Jan. 24. 1927

2 Sheets-Sheet 2

A diagram of a balance scale. It consists of a horizontal beam with a central vertical line. On the left side, there are two small weights (represented by small rectangles) and a larger weight (represented by a larger rectangle). On the right side, there is a single small weight (represented by a small rectangle). The beam is balanced horizontally.

UNITED STATES PATENT OFFICE.

HERBERT C. SMITH, OF GASTON, OREGON, ASSIGNOR OF ONE-HALF TO GLENN T. STAPLETON, OF HILLSBORO, OREGON.

COMBINED TOY AND EXERCISER.

Application filed January 24, 1927. Serial No. 163,090.

- The invention is in the nature of a child's rocking horse and it aims to provide a new and improved device of this general character in which novel provision is made whereby the child may cause the device to forwardly creep across the floor if desired, provision being made however for throwing the creeping means out of play when rocking in one position only is desired.
- 10 With the foregoing in view, the invention resides in the novel subject matter herein-after described and claimed, the description being supplemented by the accompanying drawings.
- 15 Figs. 1 and 2 are vertical longitudinal sectional views through a device constructed in accordance with the invention, showing different positions of parts.

Fig. 3 is a top plan view.

- 20 Figs. 4 and 5 are vertical transverse sections on lines 4—4 and 5—5 of Fig. 1.
- Fig. 6 is a detail horizontal sectional view showing the two pairs of rockers locked against relative pivotal movement.
- 25 Fig. 7 is a vertical transverse section substantially on line 5—5 of Fig. 1, showing the two pairs of rockers locked together.

In the drawings above briefly described, the numerals 8 designate two parallel, vertically disposed side members or rockers having curved lower edges 9 to contact with the floor, said edges being of considerably less length than the overlying or major portions of said side members or rockers. These

35 members are connected by a suitable seat 10 and a handle bar 11, which hold them in rigidly spaced relation.

A second pair of rockers 12 are provided, disposed at the inner sides of the rockers 8 and having curved lower edges 13 which project forwardly beyond the edges 9. At their front ends, these rockers 12 are vertically widened as at 14, and by suitable pivots 15, these widened ends are pivoted to the rockers or side members 8, the pivots being above the edges 9 and in front of the seat 10. Near the front edges of the widened rocker portions 14, the rockers or side members 8 are preferably provided with stop pins 16 which limit the relative tilting of the two pairs of rockers.

45 A foot board 17 rigidly connects the front portions of the rockers 12, and the rear ends of the latter are rigidly connected by a transverse bar 18. Pivoted at 19 upon this

transverse bar, is a locking bar 20. When this bar is swung to the position shown in Figs. 1 and 3, pivotal movement of the two pairs of rockers with respect to each other is permitted, but when bar 20 is swung to a position longitudinally of the bar 18, it projects beyond the rockers 12, its ends being then receivable in grooves 21 which are formed in the inner sides of the rockers or members 8. Thus, the two pairs of rockers 60 are held against relative pivotal movement and when they are so locked, the edges 13 of the inner rockers 12 are a slight distance below the edges 9 of the outer rockers or side members 8 as seen in Fig. 7. Thus, the 70 device may be effectively used for rocking only.

When the bar 20 is in released position as shown for instance in Fig. 1 and the occupant rocks the device forwardly and rearwardly, the two pairs of rockers tilt with respect to each other about the pivots 15, and the relative movements which thus take place, cause forward creeping of the device over the floor. In this connection, attention 75 is invited to the fact that when the device stands as in Fig. 1, a certain distance A exists between the front ends of the rockers 12 and the front ends of the rockers 8, whereas, when the device is rocked to the position of Fig. 2, the relative pivotal movement of the two pairs of rockers is such that the aforesaid distance shortens, as indicated at A' in Fig. 2. In other words, as the device 80 is rocked forwardly and the front portions 85 of the edges 13 engage the floor and support the weight, the rockers 8 rock slightly about the pivots 15, causing them to advance to some extent. Then, when the device is rearwardly rocked, the runners 8 support the 90 load at the positions to which they have been advanced. Thus, by shifting the weight of the body and rocking the device forwardly and rearwardly, it is caused to creep over 95 the floor.

100 Whenever the device is to be used for rocking without forward creeping, the bar 20 may be moved into engagement with the notches 21, throwing the creeping means 105 out of play. When the device is in condition either for mere rocking or for rocking and creeping, it not only produces a great deal of amusement and pleasure to the occupant, but it constitutes an effective exerciser and general developer.

As excellent results are obtainable from the details disclosed, such details may well be followed. However, within the scope of the invention as claimed, variations may be made.

I claim:

1. A device of the class described comprising two side members disposed in parallel vertical planes and elongated horizontally, said side members having curved lower edges of considerably less length than the major portions of said members, a transverse seat interposed between and secured to the upper rear portions of said side members, a transverse handle bar extending between and secured to the upper front portions of said side members, a pair of rockers disposed at the inner sides of said side members, said rockers having relatively narrow rear portions downwardly spaced from the aforesaid seat and being provided with vertically widened front end portions disposed in front of said seat, said front end portions projecting forwardly beyond said curved lower edges of said side members, transverse pivot means connecting the upper ends of said widened end portions of the rockers with said side members at points spaced in advance of the seat, a transverse foot board extending between the widened front ends of said rockers and secured thereto, and a transverse bar extending between and secured to said relatively narrow rear end portions of said rockers.
2. A device of the class described comprising two side members disposed in parallel vertical planes and elongated horizontally, said side members having curved lower

edges of considerably less length than the major portions of said members, a transverse seat interposed between and secured to the upper rear portions of said side members, a transverse handle bar extending between and secured to the upper front portions of said side members, a pair of rockers disposed at the inner sides of said side members, said rockers having relatively narrow rear portions downwardly spaced from the aforesaid seat and being provided with vertically widened front end portions disposed in front of said seat, said front end portions projecting forwardly beyond said curved lower edges of said side members, transverse pivot means connecting the upper ends of said widened end portions of the rockers with said side members at points spaced in advance of the seat, a transverse foot board extending between the widened front ends of said rockers and secured thereto, a transverse bar extending between and secured to said relatively narrow rear ends of said rockers, and a locking bar pivoted upon the upper side of this transverse bar, said locking bar being swingable either to a longitudinal position or to a transverse position, the inner sides of the aforesaid side members being provided with grooves to receive the ends of said locking bar when the latter is swung to said transverse position, whereby the side members and rockers are held against relative movement about the aforesaid pivot means.

In testimony whereof I have hereunto affixed my signature.

HERBERT C. SMITH.
